UNITED STATES PATENT OFFICE.

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA.

WEB-PRESS.

1,238,614.

Specification of Letters Patent. Patented Aug. 28, 1917.

Application filed April 26, 1915, Serial No. 23,837. Renewed July 5, 1917. Serial No. 178,785.

To all whom it may concern:

Be it known that I, HENRY A. WISE Wood, a citizen of the United States, residing at New York, in the county of New York and 5 State of New York, have invented a new and useful Web-Press, of which the following is a specification.

This invention relates to presses particularly double width newspaper presses, and 10 the principal object thereof is to provide means whereby the staggering of the plates on the plate cylinder in such a press will be prevented from causing any unequal strains in the web. These render the web taut at 15 one side and loose at the other which ordinarily causes frequent fractures of the web.

Reference is to be had to the accompanying drawings in which—

Figure 1 is a side view of a double width 20 web press constructed in accordance with this invention; and

Fig. 2 is a plan of the same.

In all double width newspaper presses having four plates abreast, running cross-wise of the press, a full width web is used. 25 After such a web has been printed it is then slit in half, and if its two halves are to be associated they are brought together either before or after the operation of folding. A full width web thus slit would produce an 30 eight page paper. Sometimes, however, when six pages need to be run on a press, the web will be three pages wide instead of four, one of which pages is slit off from the other 35 two and is thereafter associated with them to make up a six page product.

On four-page-wide presses it is the rule to have the two plates on one end of a cylinder and the two plates on the other end so 40 differently set with respect to their margins across the press that when the impression cylinder is passing over one margin it is supported by the plates at the opposite end of the cylinder, and when it is passing over 45 the margin at the opposite end of the cylinder it will be supported by the plates at the near end. This is referred to technically as "staggering plates". This has been found necessary as cylinders of such great length 50 are apt to spring down into a margin if it runs throughout their full length, and bound up when the cylinder comes in contact with the leading edges of the next plates to be

met. It is obvious that the staggering of plates obviates this trouble.

The staggering of the plates, however, is deleterious to the operation of the machine at high speed, because staggered plates release their hold on the web, first on one side and then on the other, and not simultaneously full across the width of the web. Thus the release of the web is staggered, as are the plates, which staggered release makes the web both alternately taut and loose at each side—taut at one side when it is loose at the other, and vice versa. The fact that the differing and contrary strains are set up in the same web causes frequent fractures of the web, particularly at speed.

Now in order to avoid this, according to 70 this invention, I slit the web before it goes to the printing cylinders, and thus, while using a single web roll, I am printing on a plurality of webs, each independent of the other. In this way neither web is subjected 75 to a staggered effect, but throughout its full width receives uniform tension, notwithstanding the fact that I have retained the advantage of staggering the plates themselves.

Ordinarily the two webs may be run side by side through the press as if they were one. This, with good paper and careful pressmanship, is practicable, but with poor paper and pressmanship these independent 85 webs may occasionally wander, when the edge of one may mount on top of the edge of the other and give trouble.

To prevent this I use two pathways so that from the moment the web is slit into two, 90 each of the two has a pathway of its own except while passing through the printing cylinders. In this way the wandering of the webs, which usually results between the printing cylinders and the folder, cannot 95 cause them to interfere with each other.

Referring to the drawings in detail, A and B are the two printing couples and C and D their respective inking apparatuses. Four plates P are shown staggered on each 100 plate cylinder. The web is fed into the machine from paper rolls 10 as usual, and through feeding roller 11 with its feed belts 12. As the web passes over the feed roller 11 it is shown as being slit by means of a 105 slitter 13 driven from the roller 11 through

gears 14 and 15. Of course the slitting operation can be performed at some other point. From this point the slit parts of web are guided to the first printing couple 5 independently of each other and preferably are separate as shown, one part bending over a roller 16 and the other over a roller 17. These rollers are of full width and are shown as out of registration with each other. 10 But the webs enter the printing couple A side by side. As they leave the printing couple B they are again separated, one part passing over rollers 18, 19, 20, 21 and 22 into the folder E and the other over rollers 15 23, 24 and 22 into the folder E. Of course the usual turning bars may be employed, or the two webs treated in any other manner, as if they had been individuals from the start. 20 By this construction it is possible to utilize staggered plate cylinders and at the same time allow the two parts of the web to adjust themselves to any strain or slackness every time the margin openings of the 25 printing cylinders pass each other.

Although I have illustrated and described only a single embodiment of the invention, I am aware of the fact that many modifications can be made therein by any person skilled in the art without departing from the scope of the invention as expressed in the claims. Therefore, I do not wish to be limited to the details of construction herein shown and described, but what I do claim 30 is:—

1. In a printing press, the combination with the printing couples having a plurality of sets of plates located in staggered relationship, of means for slitting the web before it passes to the printing couples, and means for conducting the parts of the web 40 through the press independently of each other.

2. In a printing press, the combination 45 with a printing couple having a plurality of sets of plates thereon located in staggered relationship, of means for slitting the web before it passes to the printing couple, and means for conducting the parts of the

web through the press in different paths independent of each other except while passing through the printing couples. 50

3. In a newspaper printing press, the combination with a printing couple having a plurality of plates abreast staggered with 55 respect to each other at the two ends of the plate cylinder, means for slitting the web on a line corresponding with the margins at which the staggering takes place, and means for guiding the two parts of the web to the 60 printing couple in paths out of registration with each other to prevent the edges of the two parts of the web overlapping.

4. In a double width newspaper printing press, the combination of a printing couple 65 having plates located in staggered relationship on the plate cylinder thereof, with means for slitting the web, and means for conducting both halves of the web to the 70 printing couple in paths located in different planes.

5. In a double width newspaper printing press, the combination of a printing couple having plates located in staggered relationship 75 on the plate cylinder thereof, with means for slitting the web, and means for conducting both halves of the web from the printing couple in paths located in different planes.

6. In a double width newspaper printing press, the combination of a printing couple having plates located in staggered relationship 80 on the plate cylinder thereof, with means for slitting the web, means for conducting both halves of the web to the printing couple in paths located in different planes, and bringing them into the same 85 plane while they pass through the printing couples, and means for conducting the half webs from the printing couples in paths located in different planes. 90

In testimony whereof I have hereunto set my hand, in the presence of a subscribing witness.

HENRY A. WISE WOOD.
